UNITED STATES PATENT OFFICE.

HARRY J. VALENTINE, OF CLEVELAND, OHIO, ASSIGNOR TO COLUMBIAN HARDWARE COMPANY, OF CLEVELAND, OHIO, A CORPORATION OF OHIO.

UNIVERSAL VISE.

SPECIFICATION forming part of Letter Patent No. 790,540, dated May 23, 1905.

Application filed August 16, 1904. Serial No. 220,953.

To all whom it may concern.

Be it known that I, HARRY J. VALENTINE, a citizen of the United States, residing at Cleveland, in the county of Cuyahoga, State of Ohio, have invented certain new and useful Improvements in Universal Vises, of which the following is a specification.

This invention relates to vises of the class known as "universal," by which work of various characters may be clamped for planing and milling and may be held in a great number of different positions, according to the nature of the work.

The objects of the invention are to obtain simplicity, durability, and strength and to rigidly hold the clamping-jaws on their swivel connection.

These being among the ends in view, my invention consists of certain features of construction and combinations of parts, such as disclosed in the accompanying drawings, illustrating a suitable embodiment of the invention, and in which—

Figure 1 is a side elevation of the universal vise, partly in perspective. Fig. 2 is a vertical central section through the ball-and-socket connection on which the clamping-jaws are adjusted and through the leverage means used for locking the parts of the ball-and-socket joint; and Fig. 3 is an elevation of the lever preferably used, coöperating parts being in section.

Referring to the drawings, the base *a* of the vise is shown as supporting a back jaw *b* and a movable jaw *c*, the faces of these jaws being preferably lined with hard steel. The means whereby the movable jaw is adjusted to or from the relatively stationary back jaw *b* are not shown in detail, as any suitable and well-known means may be used for that purpose. It will be understood that the lever device *d* acts on a suitable screw-spindle or the like, which in turn acts to adjust the movable jaw relatively to the fixed jaw *b*. The shank *b'* of the back or fixed jaw *b* is provided with a ball or head *e*, which is formed with a socket *e'*, preferably closed, as by a plug *e''*, and which has bearing in a pocket or socket *a'*, located on the base *a*, thus forming

a ball-and-socket joint. A locking-head *f* is located in the socket *e'*, and they together form a ball-and-socket locking connection between the clamping-jaws and suitable leverage means which is actuated for the purpose of binding the head *f* in the socket *e'*, whereby the movable jaws may be held rigid or locked, whether they have been inclined to one side of the axis of the stem *f'* of the head, as shown in dotted lines in Fig. 2, or whether they have been turned around said axis, as on a swivel-joint. The head *f* and socket *e'* also form a swivel-joint. The stem *f'* of the head *f* passes through a preferably enlarged opening *a²* in the base *a* and extends into a recess *a³*, located in the bottom of the base. The socket *e'* is contracted at *e³* to retain the ball upon the base and the locking-head *f*, and from its contracted opening the wall of the ball is flared to provide a flaring portion, which precludes interference of the stem *f'* therewith in all inclined positions of the back jaw-shank. Arranged in the said recess *a³* is a suitable lever *g*, preferably of the first order, and which is provided with an intermediate fulcruming portion or knuckle *g'*, that bears against the top wall of the recess *a³*. The short arm of the lever-arm is provided with an aperture *g* somewhat larger than the stem *f'* of the locking-head *f*, which passes therethrough, said stem having applied to its outer end a nut or abutment *k*, upon which the short arm of the lever is adapted to bear. An enlarged aperture *i* is located in the longer arm of the lever *g*, and passing therethrough is screw-spindle *j*, the thread *j'* of which turns in a correspondingly-threaded portion *j''* of the base *a*. That end of said spindle which passes through the aperture *i* is provided with a nut or abutment *k*, which is adapted to exert pressure on the lever when the spindle is properly rotated. A suitable lever or winch *l* acts on the spindle *j* for turning it and moving it in one or the other direction longitudinally of its axis.

The embodiment of the invention illustrated acts as follows: When it is desired to loosen the locking connection at *f e'*, the screw-spindle *j* is turned on its axis, so as to

move it in the direction of the arrow, Fig. 2, thereby relieving the pressure on the lever *g*, so that it may move into the position shown in dotted lines in Fig. 2, and unloosening the head *f*. The clamping-jaws are then free to be moved into any desired position, whereby a universal adjustment is obtainable. When the clamping-jaws have been moved, say, to the position indicated in dotted lines in Fig. 2, the screw-spindle *j* is turned so as to move it in a direction opposite to that indicated by the arrow, thereby actuating the lever, causing the same to rock on its knuckle or fulcrum *g'* and to exert a powerful leverage upon the locking-head *f* of the stem *f'* and abutment *k*, so that the internal head *f* is caused to firmly and rigidly bind upon the ball *e*.

It is evident that the construction shown may be altered in several respects and that parts may be omitted and parts added by skilled mechanics without departing from the spirit and scope of the invention—as, for instance, the connection between the back jaw and locking-lever may be modified.

Having thus described my invention, what I claim as new, and desire to secure by Letters Patent, is—

1. In a vise, the combination of a base, universally-adjustable jaws, an internal lock in a portion of one of the jaws, and leverage means for acting on said lock, and having a suitably-supported longitudinally-movable and rotary operating screw-spindle said spindle being threaded into the said base, substantially as described.

2. In a universal vise, the combination of clamping-jaws, a base, a ball-and-socket joint connecting the jaws with the base, an

internal lock in a part of one jaw for fixing the jaws in adjusted position on the base, and means connected with the internal lock, and having a longitudinally-movable and rotary screw-spindle threaded into the base to act thereon to affect said lock, substantially as described. 4c

3. In a universal vise, the combination of the base, clamping-jaws mounted for adjustment thereon in a plurality of positions, a lever, a screw-spindle acting on one end of said lever, and a ball-and-socket lock between the lever and one jaw, said lever having a knuckle or fulcrum-piece thereon located between the ball-and-socket lock and the screw-spindle and bearing upwardly on the base, substantially as set forth. 5c

4. In a universal vise, the combination of the base, clamping-jaws, one of which is provided with a ball, said base being provided with a pocket or socket in which the head is adapted to swivel, a ball-and-socket lock for the head and jaws, the head or ball thereof being provided with a stem and the base with an aperture through which said stem passes, a lever having a bearing-point at the under side of the base, a screw-spindle mounted for longitudinal movement in the base and acting on the lever, and an abutment on said stem upon which the lever is adapted to press, substantially as set forth. 6c

Signed at Cleveland, Ohio, this 8th day of August, 1904. 7c

HARRY J. VALENTINE.
